COVER BREAKING MECHANISM

Pierre Lariviere, Champlain, N. Y., assignor of
one-half to The Sheridan Iron Works and one-
half to T. W. & C. B. Sheridan Company, cor-
porations of New York

Application October 3, 1935, Serial No. 43,301

8 Claims. (Cl. 11—3)

This invention is a novel cover breaking or book back shaping mechanism, available for the shaping or squaring of covers attached to the backs of books, pamphlets and the like, and the squeezing of the book backs and covers snugly into their desired form. The mechanism hereof is particularly useful as one of the successive mechanisms in an automatic book or pamphlet covering or binding machine of the kind 5
10 wherein the books travel in series with continuous motion through the machine, of which there are several known types. An example of such a machine is that illustrated in the patent of Bredenberg 1,248,252 of November 27, 1917 wherein the 15 procession of books is advanced or forwarded edgewise through the machine by means of an endless train of individual book clamps, constituting a conveyor; and for purposes of illustration the present invention is shown as applied to 20 a machine of that type. The invention however is applicable to other types of machine, for example that shown in patent of Kleineberg 1,720,680 of July 16, 1929 wherein the conveyor for the books consists, not of individual clamps, but of 25 opposite elongated endless conveyor chains or connected series of squeezing plates or members between which the advancing books are held.

The general objects of the present invention are to afford a cover breaking mechanism operable in a manner to coordinate its action accurately with the travel of the books, and by a mechanism which is simple, rugged and compact, and which, in operation, is efficient and powerful, to the improvement of the product or finished 30 book. In the aspect that the mechanism not only breaks and squares the cover but squeezes and shapes the back of the book the invention may be available for the latter purpose without respect to the applying of covers.

40 Other objects and advantages of the invention will be explained in the hereinafter following description of an illustrative embodiment thereof or will be manifest to those conversant with the subject. To the attainment of such objects 45 and advantages the present invention consists in the novel cover breaking mechanism and the novel features of combination, arrangement and construction herein illustrated or described.

In the accompanying drawings Figure 1 is what 50 may be termed an end elevational view of a cover breaking mechanism embodying the invention, with certain longitudinal parts shown in trans-verse section.

55 Fig. 2 is a top plan view of the mechanism shown in Fig. 1. In Figs. 1 and 2 the cover

breaking jaws or plates are shown in their operative position with the book and cover squeezed under pressure between them, Fig. 2 showing in dotted lines the normal retracted position before operation.

Fig. 3 is a perspective view of one of the jaws and the parallel arms on which it is mounted, broken open to show the preferred connection between them.

Figs. 4, 5 and 6 are plan view diagrams, showing successive positions in the operation of the mechanism.

Fig. 1 shows the usual relation between the book B and the cover C, corresponding to Figs. 14-16 of the Bredenberg patent. Some of the usual general parts of the machine include the central longitudinal frame member 10 from which extend laterally at intervals transverse frame members 11, at the extremities of which are carried the longitudinal tracks 12 in which run the rollers (not shown) that carry the clamps 13. The articulated clamps and their rollers constitute the book conveying means.

Below the path of the book is an upstanding frame post 15, at the top of which is supported a fixed transverse table 16 which may consist of cross bars acting as supports and guides for sliding carriages to be mounted. Above the central part of the table are shown the mountings 17 of a longitudinally traveling member 18 in the nature of a band, plate or series of plates, operating as a back pressing means. This is a well known device in book covering machines adapted to bear against the back edge of the book during the breaking operation. The member 18, sometimes in the form of an endless band, is usually first employed as a cover applier to bring the cover C up to the glued back of the book and press it there, continuing its pressure through the cover breaking operation; and the member 18 may be considered as a cover applying and cover pressing means or member.

The cover breaking means comprises primarily a lift or outer jaw or breaker plate 20 and an opposite corresponding right jaw or plate 20^a. These opposing jaws are shown as straight-edged rigid plates, and they work cooperatively to apply squeezing pressure to the lower back edge of the book during its forward travel, which is preferably continuous. In general, the parts 20 etc. at the left side of the book travel are shown duplicated at the right side with the same numbers and the exponent "a". However this invention can be used either at both sides or at one side only, and in the latter case with a

suitable cooperating device or abutment at the other side working in coordination with the jaw.

The jaw hereof, or each of the jaws, is mounted and operated in a novel manner. The jaw is fitted for transverse shifting movements to and from the book path, and also for advance and return movements longitudinally of the book path. There is an automatic means for shifting the jaw to the book to close into contact therewith, namely, when in opposition to the book. There is a means for causing the jaw to advance longitudinally along the book path while in contact with the book, this being actuated from the book conveyer, specifically by friction from the book itself. Finally, this combination includes means operating during the jaw advance to cause the jaw to press wedgingly, as by cam or toggle action, against the book for heavy squeezing pressure thereon.

The particular arrangements for carrying out this plan may be varied widely. The wedging action might be by rollers and cams, but is shown as produced by a swinging arm, on which the jaw is mounted, acting like a toggle on the jaw by reason of its swinging toward a position at right angles to the travel. Two such arms are shown for each jaw, as a convenient means of maintaining parallelism of the jaw to the book path. The jaw and its mountings may be bodily shiftable to the book for each operation, for example, by being carried on a carriage, shifted automatically at the proper time.

In the specific form shown the left breaker jaw 20 is mounted at the inner ends of a pair of parallel arms 21, and the right breaker jaw is similarly mounted and carried on parallel arms 21a. By this arrangement, both of the jaws are at all times parallel to the longitudinal direction of book travel. An effective and compact arrangement for mounting each of the jaws upon its carrying arms is as shown in detail in Fig. 3. The inner extremity of each of the arms 21 is formed with a thin circular end portion 22. The jaw or plate 20 is shown as having a thin outward extension 23 underlying the end 22 of the arm, while overlying said end is a top or cover piece 24 detachably secured to the jaw. These parts 22, 23 and 24 are suitably apertured to receive a collared stud 25, which is thus confined in place as shown 50 and forms an effective pivot for the relative motion as the arms swing.

At their outer ends, each of the pair of arms 21 for its swinging movement is mounted at the top end of an upright fulcrum shaft 27 turning in ball bearings in a hollow boss 28. The two bosses for each pair of arms are formed or mounted upon a common carriage 29. This carriage is constructed and fitted to slide transversely upon the table or guide 16 for the inward or closing shift of the jaw and its retraction. The shaft 27 is shown inclined slightly from the vertical, as are the arms 21 and jaw 20 inclined from the horizontal, this arrangement affording a more practical cooperation with the advancing book and cover and the underlying presser 18.

The closing movement of the breaker jaws upon the book is effected by sliding toward each other the opposite carriages 29 and 29a. This and the subsequent retracting movement of the carriages are effected in timed relation to the advancing travel of the books, and the connections for this purpose may be as follows. Attached to the left carriage 29 is a long underneath link 30 and attached to the right carriage 29a is a short upper link 30a. These two links extend respectively to

the lower and upper extremities of a rocker or lever 31 mounted on a longitudinal shaft 32 fulcrumed upon fixed frame brackets 33. By this arrangement, the swinging of the rocker in one direction causes both carriages to approach each other and thus bring the breaker jaws to the book, while the opposite swing of the rocker retracts the carriages and jaws, with a shifting movement of small extent.

Operating connections for the rocking movement are shown as follows. An extension 34 of the rocker lever carries a cam follower 35 at its extremity, a spring 36 being arranged to pull the arm 34 and so keep the roller against its cam 36. For the major part, the cam 36 consists of a dwell, whereby the cam roll takes the dotted line position, corresponding to the outward retracted position of the jaws; but the cam has a steep rise which throws the roll outwardly to the full line position and thus shifts the carriages and jaws, the latter then coming together upon the book for a brief period of squeezing pressure, following which the rise passes from under the roll and the carriages and jaws again retract. The cam 36 is shown mounted on a shaft 37 which is rotated by gears 38 from a longitudinal shaft 39, which may be the main shaft of the machine; the gearing being such that the cam 36 makes a complete rotation in each cycle of the machine, corresponding to the passage of each clamp and book through the cover breaking position.

As the link 38 forces inward the carriage 29 to bring the jaw 20 to the book, this inward movement should be varied in accordance with the thickness of the book, and a convenient adjustment for thickness may be as follows. Where the link is connected to the carriage the link is threaded and is engaged in a threaded head 40, so that by turning the link its effective length is varied for the purpose stated. When the adjustment is obtained the lock nuts 41 at the other end of the link operate to hold the adjustment.

When the jaw or jaws are brought into contact with the book they are advanced therewith in a passive manner, the supporting arms swinging as the travel of the conveyor and book operates to advance the jaw. When subsequently retracted the jaw must be returned to its initial position to operate on the next book. A stop 42 is shown against which one of the arms contacts when the jaw is in initial position, as seen in Figs. 4 and 5. To return the jaw to this position there is shown a spring 43 operating upon one of the arms, to pull the arms and jaw until the cushioned stop 42 is encountered.

The mode of operation will be clear by comparison of Figs. 4, 5 and 6, the last of which corresponds in position with Figs. 1 and 2. In the normal or idle position of Fig. 4 each jaw has been retracted outwardly and between the jaws is a space wider than the thickness of the book; and the spring 43 has returned the jaw into a position with the arm 21 contacting the stop 42. A longitudinal dotted line shows the retracted position of the pivotal mounting 27 of the arm 21 upon the shifting carriage. The book B is shown as traveling advancingly toward the observer.

About this time the cam 36 commences action to move inwardly each of the carriages and thereby close the jaws upon the book. By the time the jaws have contacted the book the book has advanced as shown in Fig. 5, so that its entire length may be squeezed between the jaws. The longitudinal dotted line in Fig. 5 shows that

each carriage has moved inwardly by the slight extent necessary for this operation. The arm 21 is still in contact with the stop 42. The travel of the conveyor now operates upon each 5 jaw to compel its advancing travel with the book. Specifically the friction between the jaw and book causes the jaw to advance. By this dragging action the book supplies the power to advance the jaws and thereby cause their squeezing 10 movement toward each other, as by the toggle action illustrated, so that in effect the book performs its own squeezing operation, requiring no other connection for swinging the arms.

When the two arms have swung into alignment 15 or dead center, as shown in Fig. 6, the maximum squeezing action is in effect, thus effecting the breaking of the cover as desired. The movement may be continued substantially beyond the position of Fig. 6, which corresponds also with 20 Figs. 1 and 2, and after a suitable extent of travel the jaws are to be retracted, becoming free from the book, thereby permitting the springs to return the arms and jaws to the initial position of Fig. 4.

25 This generally described action may be specially modified by selecting a suitable contour to the cam 36. Thus the period of squeezing pressure may be somewhat prolonged by timing the cam 36 to allow a slight relaxation of 30 pressure upon the carriages slightly before the arms reach the dead center position of Fig. 6. This is herein shown from the fact that the cam 36 has slightly passed its apex at the position of 35 dead center. A destructively high squeezing pressure is avoided, while permitting a prolongation of the squeezing action and a pressure of any desired magnitude.

It will thus be seen that I have described a machine of the kind referred to, constructed 40 according to the principles and attaining the objects and advantages of the present improvement. Since many features including matters of combination, arrangement and construction may be variously modified without departing 45 from the underlying principles, it is not intended to limit the invention to such features except in so far as set forth in the appended claims.

I claim:

1. In combination with a book conveyor for 50 clamping and advancing books edgewise in longitudinal procession, a cover breaking mechanism operative upon the back of each book while being so advanced, comprising a straight breaker jaw laterally adjacent the book path, at one side, 55 and a straight breaker member in opposition to said jaw at the other side, a carriage for the jaw, said carriage being mounted for transverse closing and retracting movements to carry the jaw to and from the book path, the jaw having means mounting it movably upon the carriage to 60 receive advance and return movements longitudinally of the book path, and having means operative during and by reason of its advance movement to cause it to press wedgingly against the book for heavy squeezing pressure thereon, timed means for closing the carriage toward the conveyor and book thereby to close the jaw into contact with the book when in opposition thereto, and means for advancing the conveyor and 65 therefrom causing the jaw to advance longitudinally along the book path while in contact with the book, whereby the book is squeezed wedgingly during its travel.

2. The combination as in claim 1 and wherein 70 is a stop means to determine the normal re-

turned position of the jaw, and spring means to return the jaw and its mounting to such normal position when released by the retraction of the carriage.

3. The combination as in claim 1 and wherein 5 the mounting of the jaw upon the carriage comprises a swingable arm with pivot located to afford a toggle like pressing action as the jaw advances.

4. The combination as in claim 1 and wherein 10 the mounting of the jaw upon the carriage comprises a swingable arm with pivot located to afford a toggle like pressing action as the jaw advances, with a stop for the return swing of 15 the arm and a spring to return it.

5. In combination with a book conveyor for 20 advancing books edgewise in longitudinal procession, each with its back protruding and cover adhering thereto, a cover breaking mechanism operative upon the back and cover of each book 25 while being so advanced, comprising a back pressing member traveling in contact with the back of the book, a straight breaker jaw at each side of the book path, a carriage for each jaw, 30 said carriages being mounted for transverse shifting movements to close the jaw to the book path, each jaw having means mounting it movably upon the carriage to receive advance and return movements longitudinally of the book path, with means normally positioning it ahead of its 35 squeezing position, and having means operative during and by reason of its advance movement to cause it to press wedgingly against the book for heavy squeezing pressure thereon, timed 40 means for shifting the carriages toward the conveyor and book to close the jaws into contact with the book when in opposition thereto, and means for advancing the conveyor and by reason of such advance causing the jaws to advance longitudinally along the book path while in contact with the book, whereby the book is squeezed 45 wedgingly during its travel and the cover is broken thereon.

6. The combination as in claim 5 and wherein 50 the carriage shifting means comprises a rocker, having connections to the respective carriages for shifting them, means for adjusting such connections for differences in book thickness.

7. In combination with a book conveyor for 55 advancing books edgewise in longitudinal procession, a book back shaping mechanism operative upon the back of each book while being so advanced, comprising a straight breaker jaw at one side of the book path, and a breaker member constituting an abutment at the opposite side, a 60 carriage for the jaw, said carriage being mounted for transverse shifting movements to carry the jaw to and from the book path, the jaw having means mounting it movably upon the carriage freely to receive advance and return movements longitudinally of the book path, with means returning it to a normal position ahead of its squeezing position, and having means operative 65 during and by reason of its advance movement to cause it to press wedgingly against the book for heavy squeezing pressure thereon, timed means for shifting the carriage toward the conveyor and book to close the jaw into direct contact with the book when in opposition thereto, 70 and means for advancing the conveyor with book and thereby causing the jaw by its frictional grip upon the book to be advanced longitudinally along the book path, whereby the book during its travel is subjected to heavy squeezing pressure. 75

8. In combination, a conveyor for conveying books edgewise with their back edges projecting, a straight jaw at one side of the travel path, and a breaker member constituting an abutment at 5 the opposite side, a carriage for the jaw, mounted in the machine to shift laterally inward toward and outward from the book path, the jaw being mounted on the carriage to partake of its inward and outward movements but free to be 10 moved thereon longitudinally of book travel and having means to wedge it inwards relatively to the carriage during its longitudinal advance

thereon, timed means to move inward the carriage and jaw to bring the jaw to each traveling book, and subsequently to retract outwardly after the book squeezing operation, and means coordinately to advance the conveyor thereby to advance the book and to provide the actuation for the advancing movement of the jaw by contact of the jaw with a part traveling with the conveyor which part may be the book itself, whereby the jaw while advancing with the book presses 10 wedgingly against it. 5

PIERRE LARIVIERE.
